(57) **CLAIM**

The ornamental design for a waterfall kitchen sink as shown and described.

DESCRIPTION

FIG. 1 is a perspective view of a waterfall kitchen sink showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a view of a waterfall kitchen sink in use;

FIG. 10 is another view of a waterfall kitchen sink in use;

FIG. 11 is an enlarged view of the encircled portion in FIG. 3; and,

FIG. 12 is an enlarged view of the encircled portion in FIG. 1.

The broken lines in the drawings illustrate the portions of the waterfall kitchen sink, which form no part of the claimed design. The dot-dash broken lines in FIG. 1 and FIG. 3 represent the boundary of the enlarged portion and form no part of the claimed design.
